UNITED STATES PATENT OFFICE.

CLARENCE E. LOMAX, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TELEPHONE SYSTEM.

Application filed November 15, 1921, Serial No. 515,287. Renewed May 7, 1926.

The present invention relates to telephone systems in general, but is concerned more particularly with telephone systems comprising both manual and automatic exchanges; and the principal object, briefly stated, is the production of new and improved circuit arrangements whereby the operation of the apparatus employed whenever a connection is set up from a manual to an automatic exchange is improved so as to make it more satisfactory and desirable.

A special object is to provide circuit arrangements such that a "B" operator is given a flash recall when a trunk leading to her position is taken for use a second time before the first connection has been taken down.

Other objects, which have to do with the carrying out of the general scheme and which will not be mentioned specifically at this time, will be explained fully hereinafter, reference being had to the accompanying drawings comprising Figs. 1-3, inclusive, which when arranged in order with the corresponding lines at the ends thereof in alignment show all the apparatus necessary for a complete connection between a calling substation A in the manual exchange and a called substation A' in the automatic exchange.

The apparatus shown in Fig. 1 is assumed to be located in the manual exchange while the apparatus shown in Figs. 2 and 3 is assumed to be located in the automatic exchange, although if desired the apparatus shown in Fig. 2 may be located in the manual exchange also.

The substation A is an ordinary manual substation and is connected with the central exchange by means of the two conductors 11 and 12 as shown.

The "A" operator's cord circuit O is of a well-known type and in the present instance is used to connect the calling line with a trunk leading to the exchange in which the called line terminates.

The operator's plug ending trunk circuit O', Fig. 2, is permanently associated with the selector D by means of the conductors 66 and 67, as shown, and is used to connect the selector D with one of a plurality of

trunk lines of which the trunk line comprising conductors 22 and 23 is one. This trunk circuit is shown complete and will be explained fully hereinafter.

The selector D, Fig. 3, as well as the connector H, is an automatic switch of the well-known vertical and rotary type and accordingly has its bank contacts arranged in horizontal rows or levels. The circuits of these switches are not novel and since they are well known they need not be described. It will suffice to say that these switches are operated according to the well-known two-wire system of control. Most of the circuits of the connector H have been omitted for the sake of simplicity, only the line, release, and back bridge relays being shown.

The line switch C in which line of the automatic substation A' terminates is of the well-known rotary type in which the wipers have no normal position and move in a forward direction only. The circuits of this switch also are well known and consequently need no description.

The apparatus, having been described in general, will now be described in connection with a more or less detailed description of its operation. For this purpose it will be assumed that the subscriber at substation A in the manual exchange desires to obtain connection with the subscriber at substation A' in the automatic exchange. When the receiver is removed at substation A, a circuit is closed over line conductors 11 and 12 for line relay 13. Line relay 13, upon energizing, closes a circuit for the line lamp L at armature 17', whereupon the said lamp L becomes lighted. The operator, upon noting the lighted condition of the lamp L, inserts the answering plug of an idle cord circuit into the jack J, the plug P of the cord circuit O for example. When this is done, cut-off relay 14 energizes in series with the lamp L' and disconnects line relay 13 at armature 15, and removes ground from conductor 12 at armature 16, whereupon line relay 13 deenergizes, thereby extinguishing the lamp L. Supervisory relay 17, upon energizing over the calling subscriber's loop, places a shunt around the supervisory lamp

90
95
100

L', thereby preventing the said lamp from becoming lighted at this time.

The operator now throws the key K, which is a combined listening and ringing key, into 5 listening position, thereby connecting up the leads associated with her head set. She now converses with the calling subscriber and after ascertaining the exchange in which the line of the desired subscriber terminates, she 10 restores the key K to normal and inserts the plug P' into a jack which we shall assume is the jack J², the associated trunk being idle as indicated by the unlighted condition of the lamp L³. When the plug P' is inserted into 15 the jack J², sleeve relay 21 energizes in series with the supervisory lamp L² and the said lamp L² becomes lighted. Upon energizing, relay 21 closes a circuit for the busy lamps L³ and L⁴, whereupon the said lamps 20 become lighted.

In the automatic exchange, the high resistance line relay 30, upon energizing over the loop comprising trunk conductors 22 and 23 and the calling end of the cord circuit O, closes a circuit for the line lamp L⁵, whereupon the said lamp becomes lighted. Supervisory relay 18 in the cord circuit O, however, does not energize at this time owing 25 to the high resistance of line relay 30.

30 The "B" operator, upon noting the lighted condition of the line lamp L⁵, inserts a plug associated with an idle trunk circuit into the jack J³, the plug P² associated with the trunk circuit O' for example. When the 35 plug P² is inserted into the jack J³, line relay 30 is disconnected and, upon becoming de-energized, extinguishes the line lamp L⁵. As a further result of the plug P² being inserted 40 into the jack J³, the upper and lower left hand windings of the repeating coil associated with the plug P² and the high resistance relay 31 are bridged across the conductors 22 and 23 in series. Supervisory relay 18 of the cord circuit O does not energize at 45 this time either, owing to the high resistance of supervisory relay 31 in the trunk circuit O'. Relay 31, upon energizing, disconnects the lamp L⁶ from the sleeve conductor 69 of the plug P² and connects it to armature 46 of 50 relay 35 at armature 38. As a still further result of the plug P² being inserted into the jack J³, a ground potential is placed upon the sleeve conductor 69 of the said plug, thereby closing a circuit for the supervisory 55 lamp L⁷, which circuit includes spring 60 of the key K' and its resting contact, and armature 44 of relay 34 and its resting contact. The supervisory lamp L⁷ now becomes lighted.

60 The "B" operator now throws her key K', which is a combined calling device and listening key, into listening position, thereby connecting up the conductors associated with her head set at springs 61 and 62. She now 65 converses with the calling subscriber and,

after having been apprised of the number of the desired subscriber's line, she throws the key K' to the opposite or calling position, thereby closing a circuit for the connecting relay 36 at spring 63. Connecting 70 relay 36, upon energizing, closes a locking circuit for itself at armature 48, which circuit includes armature 37 of relay 31 and its working contact. As a further result of the energization of connecting relay 36, it 75 connects up a bridge, including the upper and lower right hand windings of the associated repeating coil and the polarized relay 32, to the springs of the key K' at armatures 47 and 49. As a still further result of the operation of the key K', a bridge, including conductors 70 and 71, contacts 68 of the release push button B, the impulse springs of the calling device S, and the secondary windings of the operator's induction coil, is placed across trunk conductors 66 and 67 at springs 64 and 65, and the said conductors 66 and 67 are disconnected from the working contacts of armatures 47 and 49.

90 In response to the placing of this bridge across the conductors 66 and 67, the line and release relays 75 and 76 of the selector D energize, thereby preparing the switch for operation in the usual manner.

95 The operator now manipulates the calling device S in accordance with the digits of the desired number, whereupon the selector D is operated in the usual manner to extend the connection to the connector H, and the 100 connector H is operated in the usual manner to finally connect with the called line. After the connection is completed, ringing current is sent out intermittently from the connector H in any well known or approved 105 manner to ring the bridged bell at the called substation.

The operator, having finished dialling the desired number, now restores the key K' to 110 normal position, thereby opening the initial circuit of connecting relay 36 at spring 63, and at the springs 64 and 65 shifting the bridge across conductors 66 and 67 so as to include the right hand windings of the associated repeating coil and polarized relay 115 32 instead of the bridge which includes the impulse springs of the calling device S. The automatic switches are now held up over the bridge including polarized relay 32, but the armature 39 of the said relay is 120 not operated owing to the fact that the current is flowing in a direction opposite to that in which it must flow in order to operate the said armature. When the subscriber at substation A' responds to the ringing of his 125 bell by removing his receiver, certain operations take place in the connector H with the result that ringing current is removed from the called line and the called line is connected up to the upper and lower windings of back 130

bridge relay 77. Back bridge relay 77, upon energizing over the called subscriber's loop, reverses the incoming trunk conductors as regards their connection with the upper and 5 lower windings of line relay 78, whereupon the polarized relay 32 in the trunk circuit O' responds by operating its armature 39, thereby closing a circuit for relay 33. Relay 33, upon energizing, closes a circuit for relay 10 34 at armature 42. Relay 34, upon energizing, extinguishes the lamp L' and closes a locking circuit for itself at armature 44, thereby giving the B operator answering supervision. As a further result of the energization of relay 33, it places a shunt around 15 a portion of the winding of relay 31, thereby lowering the resistance of the said relay sufficiently to allow supervisory relay 18 of the cord circuit O to energize. Upon energizing, supervisory relay 18 places a shunt around supervisory lamp L², whereupon the said lamp becomes extinguished to give the "A" operator answering supervision.

The calling and called subscribers may 20 now converse with each other in the usual manner, the talking circuits being outlined by the heavy conductors.

After the conversation is finished the two subscribers replace their receivers. When 25 the receiver is replaced at the substation A the circuit of supervisory relay 17 is opened and the said relay, upon becoming deenergized, removes the shunt from around the supervisory lamp L', whereupon the said 30 lamp becomes lighted.

When the receiver is replaced at the substation A', the circuit of back bridge relay 77 is opened and the said relay, upon deenergizing, reverses the incoming trunk conductors back to normal, whereupon polarized 35 relay 32 in the circuit O' responds by retracting its armature 39, thereby opening the circuit of relay 33. Upon deenergizing, relay 33 removes the shunt from around the 40 upper portion of the high wound relay 31 at armature 40, whereupon the marginally adjusted supervisory relay 18 in the cord circuit O deenergizes, thereby removing the shunt from around supervisory lamp L² and 45 allowing it to become lighted.

The A operator, upon noting the lighted condition of the lamps L' and L², knows that the conversation is completed and that the calling and called subscribers have replaced their receivers and accordingly, she pulls down the connection. When the plug P is removed from the jack J, cut-off relay 14, upon deenergizing, connects up line relay 13 again and the supervisory lamp L' in 50 the cord circuit O becomes extinguished. When the plug P' is removed from the jack J², sleeve relay 21, upon deenergizing, opens the circuit of the busy lamps L³ and L⁴, whereupon the said lamps become extinguished. As a further result of the removal 55

of the plug P' from the jack J², the supervisory lamp L² in the cord circuit O becomes extinguished. As a still further result of the removal of the plug P' from the jack J², the circuit of supervisory relay 31 in the 60 trunk circuit O' is opened and the said relay, upon deenergizing, opens the locking circuit of connecting relay 36 at armature 37. Connecting relay 36, upon deenergizing, opens the bridge across conductors 66 and 67 at 65 armatures 47 and 49, whereupon the automatic switches are restored to normal position in the usual manner. As a further result of the deenergization of relay 31, it closes a circuit for relay 35 at armature 37, 70 which circuit includes the working contact of armature 43 and said armature. Upon energizing, relay 35 closes a locking circuit for itself at armature 45 and prepares a flash recall circuit for the lamp L⁶ at armature 46. As a still further result of the deenergization of relay 31, it closes the circuit of lamp L⁶ at armature 38, whereupon the 75 said lamp L⁶ becomes lighted. Upon noting the lighted condition of the lamp L⁶, the "B" operator withdraws the plug P² from the jack J³, thereby removing the ground potential from sleeve conductor 69, whereupon the lamp L⁶ becomes extinguished and the relays 34 and 35 deenergize. 80

If we assume now that the operator, being otherwise engaged, leaves the plug P² in the jack J³ and that the trunk line comprising conductors 22 and 23 is connected within the manual exchange in the usual manner, a circuit is closed for relay 31 of the operator's 85 trunk circuit O'. Upon energizing, relay 31 disconnects the lamp L⁶ from direct ground by the way of the sleeve conductor 69 of the plug P² at armature 38, and connects it to ground by way of armature 46 and its working contact and the interrupter I. The interrupter I alternately opens and closes the circuit of the lamp L⁶ causing it to flash 90 on and off, thereby attracting the attention of the operator immediately and informing her that another call has come in over the trunk comprising conductors 22 and 23. Upon noting that the lamp L⁶ is flashing intermittently, the operator throws her key K' 95 to listening position, thereby connecting up the conductors of her head set at springs 61 and 62. As a further result of the operation of the key K', the locking circuit of relays 34 and 35 is opened at spring 60. Relay 35, 100 upon deenergizing, opens still another point in its locking circuit at armature 45 and at armature 46 disconnects the lamp L⁶ from the interrupter I, whereupon the said lamp ceases to flash. Relay 34, upon deenergizing, 105 opens still another point in its locking circuit and prepares a circuit for supervisory lamp L' at armature 44. The operator now converses with the calling subscriber in the usual manner and, after having 110

learned the number of the desired subscriber, throws the key K' to the opposite or calling position, whereupon the supervisory lamp L' becomes lighted and the operations incident to the calling of the desired number take place in the previously described manner.

It sometimes happens that, after a connection is completed, the two subscribers are not able to hear each other distinctly. Assuming now that the subscriber at substation A discovers that he cannot hear plainly enough and that the difficulty is due to a defect in the "A" operator's cord circuit, he works his switch hook up and down slowly, thereby causing the supervisory lamp L' to flash. The operator, upon noting that the lamp L' is flashing, throws the key K to listening position and converses with the subscriber. After finding out the trouble, the "A" operator changes the cord circuit O for another, whereupon the subscribers may converse in the usual manner. It will be remembered that according to the previous explanation the automatic switches are released when the "A" operator takes the connection down, which she does in effect when she changes cord circuits. The connection is not released in the present instance, however, for the reason that the called subscriber has not yet replaced his receiver and consequently relay 33 of the trunk circuit O' is operated and the connecting relay 36 is locked up to the sleeve conductor 69 of the plug P² by way of the working contact of armature 41 and said armature. As a result, the momentary deenergization of supervisory relay 31, which occurs when the "A" operator changes cord circuit, does not cause the deenergization of connecting relay 36 and the connection is held up.

Assuming now that the subscriber at substation A' has left his receiver off the hook and that the subscriber at substation A has replaced his receiver, and that the "A" operator, after waiting a reasonable length of time for the called subscriber to replace the receiver, and possibly after having failed in an attempt to converse with him, pulls down the connection, whereupon the disconnect lamp L⁶ in the trunk circuit O' is lighted in the usual manner. The "B" operator now pulls down the connection, whereupon the lamp L⁶ becomes extinguished and the connection is released in the usual manner in response to the deenergization of connecting relay 36.

If we assume, however, that before the "B" operator has had time to pull down the connection, the trunk line comprising conductors 22 and 23 is again taken for use, the "B" operator's attention is attracted by the flashing of the lamp L⁶ in the hereinbefore described manner. The "B" opera-

tor responds by throwing her key K' to listening position after which, she obtains the desired number from the calling subscriber. When the key K' is thrown subsequently to the opposite or calling position, the bridge across the conductors 66 and 67 is shifted so as to include the impulse springs of the calling device S, the secondary winding of the operator's induction coil, and the contacts 68 of the release button, B. The "B" operator is instructed to listen before operating her calling device, so as to determine whether or not any of the automatic switches are operated. In case they are not, the conductors 66 and 67 extend to the windings of line relay 75 of the selector D and the operator hears a distinctive tone which is produced by the tone machine T. But in the present case, since the conductors are disconnected from the windings of line relay 75 of the selector D and are extended to the windings of line relay 78 of the connector H, the operator not hearing the tone knows that a connection is partly or completely set up, and in order to release the automatic switches, she operates the release button B, thereby opening the bridge across the conductors 66 and 67 at the contacts 68, whereupon the automatic switches are restored to normal position in the usual manner.

When the operator releases the button B, the contacts 68 close the bridge again and as a result the line and release relays 75 and 76 of the selector D are energized, thereby preparing the switch for operation in the usual manner. The operator now completes the connection in the hereinbefore described manner.

The various features of the invention, having been described and explained, will now be pointed out in the appended claims.

I claim:

1. In a telephone system, means for connecting a calling line in one exchange with a called line in a second exchange, said means including a trunk line terminating at an "A" position in the first exchange and at a "B" position in the second exchange, a signal lamp at the "B" position, means for lighting said lamp when the "A" operator pulls down the connection in order to give the "B" operator a disconnect signal, and means for "flashing" said lamp in case the "A" operator plugs into said trunk thereafter before the connection is pulled down at the "B" position.

2. In a telephone system, a manual exchange including an "A" position, an automatic exchange including a "B" position, means for connecting a manual calling line with an automatic called line, said means including a trunk extending between said positions and a series of automatic switches directly controlled from the "B" position, a

- lamp signal at the "B" position, means for lighting said lamp to give the "B" operator a disconnect signal when the "A" operator pulls down the connection, and means for 5 automatically "flashing" said lamp in case the "A" operator plugs into the trunk again before the "B" operator has pulled down the connection.
3. In a telephone system, a trunk line extending from an "A" position in a manual exchange to a "B" position in an automatic exchange, means including said trunk line and a series of automatic switches for connecting a calling manual line with a called 10 automatic line, and a control circuit for said switches completed initially by the "B" operator, and controlled jointly by the "A" operator and by the called subscriber for preventing the release of said switches.
- 20 4. In a telephone system, manual and automatic exchanges and an interconnecting trunk line, "A" and "B" positions in the said exchanges in which said trunk line terminates, a cord circuit at the "A" position for 25 connecting a calling line with said trunk line, a local trunk line extending from the "B" position to an automatic switch, means for connecting said local trunk line with the inter-office trunk line, a key associated with 30 the local trunk, a relay responsive to the operation of said key to close a bridge across said local trunk line to complete a control circuit for said switch, a second relay controlled over said inter-office trunk line to 35 close a locking circuit for said first relay, means for operating said switch and other switches to complete the connection to a called line, a third relay responsive only while the receiver is off at the called station 40 to close another locking circuit for said first relay, and release means for said switches responsive when said bridge is opened by the deenergization of said first relay.
5. In a telephone system, a plurality of 45 subscribers' stations, lines accessible to all of said stations extending to a manual switchboard, a link circuit at said switchboard, manually controlled means at said switchboard for completing a connection from any 50 calling subscriber's station by way of one of said lines to said link circuit, a signal individual to said link circuit, means responsive to the termination of a call by the calling party for preparing said signal for operation, and means responsive to a new call over 55 the line last used before the connection has been broken down at said switchboard for operating said signal.
6. In a telephone system, lines extending 60 to a manual switchboard, a link circuit at said switchboard, means including a cord circuit for extending a call to a line, manually controlled means at said switchboard for completing a connection from any calling 65 one of said lines to said link circuit, a signal, means individual to said link circuit responsive to the termination of a call by the calling party for preparing said signal for operation, and means responsive to a new call over the line last used before the connection 70 between the line and associated link circuit has been broken down at said switchboard for operating said signal.
7. In a telephone system, a plurality of lines extending to a manual switchboard, a link circuit terminating in an automatic switch, means for setting up a telephone connection including any one of said lines, said link circuit and said automatic switch, means 75 individual to each line for informing the operator of initial calls, a signalling device individual to said link circuit, means for preparing said device for operation responsive to the calling party terminating the initial call, and means for operating said device to 80 inform the operator of a second call over the connected line.
8. In a common battery telephone system, a plurality of subscribers' stations, a plurality of lines accessible to all of said stations extending to a manual switchboard, a call-signal device individual to each line and responsive to a call from a subscriber's station over the associated line, a link circuit 85 at said switchboard for completing a telephone connection including any one of said lines, and a recall signal device in said link circuit responsive to the current flow set up from the common battery when a new call comes in over a line before a connection 90 previously set up over the same line through said link circuit has been broken down.
9. In a common battery telephone system, a manual switchboard, a plurality of lines terminating thereat, a cord circuit, a link 95 circuit for completing a telephone connection including any one of said lines and said cord circuit, means for breaking down said connection at the termination of said conversation, means for bringing in a new call 100 on the connected line and link circuit and for setting up a battery current flow thereover prior to the breaking down of a previous connection of said line and link circuit, and current-flow detecting means in said link circuit common to all said lines for apprising the operator of the new call.
10. In a telephone system, a line extending to a manual switchboard, directly operated manually controlled automatic switching means whereby the operator at said switchboard can set up a telephone connection including said line, a signal lamp at 115 said switchboard, a recall circuit for said signal lamp, a relay at said switchboard maintained operated as long as the original call remains on said line, a second relay operated responsive to the restoration of the first relay when the original call is cleared out to 120 prepare said recall circuit, whereby said re-

call circuit is completed upon the reoperation of the first-named relay when a second call comes in over said line prior to the taking down of the connection at the manual switchboard.

11. In a telephone system, a link circuit, means for extending a connection from a calling line to said link circuit, a train of automatic switches for further extending the connection from said link circuit to a called line, means in said link circuit controlled over the calling line by current flow there-over for maintaining said automatic switching mechanism operated, whereby said automatic switching mechanism may be released responsive to the stopping of the current flow over the calling line by the calling party, and means in said link circuit controlled by the responded state on the called line for rendering the releasing means of said automatic switches non-responsive to the stopping of the current flow in the calling line by the calling party while maintaining direct current flow during conversa-tion in every portion of the talking circuit extending between the calling and the called line.

12. In a telephone system, means including a train of automatic switches for setting up a telephone connection from a calling line to a called line, means for maintaining the automatic switches operated subject to the maintenance of a current flow in the calling line, and means controlled through said switches by the setting up of a current flow over the called line when the called subscriber responds for rendering the releasing means of said automatic switches non-responsive to the cessation of current flow in the calling line, while maintaining direct current flow during conversation in every portion of the talking circuit extending between the calling and called lines.

13. In a telephone system, an "A" position, a "B" position, a trunk connecting the two, a signal at the "A" position for indicating the busy condition of the end of the trunk that terminates at the "A" position regardless of the busy or idle condition of the other end of the trunk, a signal at the "B" position and means for operating the signal responsive to the seizure of the trunk at the "A" position if the trunk is idle at both positions, a second signal at the "B" position, and means for operating the last mentioned signal upon the seizure at the "A" position of the trunk if the trunk is idle at the "A" position but busy at the "B" position.

14. In a telephone system, an "A" position, a "B" position, a trunk connecting the two, a signal at the "A" position for indicating the busy condition of the end of the trunk that terminates at the A position regardless of the busy or idle condition of the other end

of the trunk, a signal at the "B" position, and means for operating the last mentioned signal upon the seizure at the "A" position of the trunk if the trunk is idle at the "A" position but busy at the "B" position, and means at the "B" position for reestablishing the initial condition of the last mentioned signal without changing the busy condition of the trunk.

15. In a telephone system, first and second operators' positions, an automatic switch, a line, a trunk connecting the two positions, means including the automatic switch for setting up a connection from the trunk to the line, a signal at the second operator's position, and means responsive to the estab-lishment of a connection to the trunk at the first position during the existence, at a second position, of a connection over the automatic switch for operating the signal. 75

16. In a telephone system, first and second operators' positions, an automatic switch, a line, a trunk connecting the two positions, means including the automatic switch for setting up a connection from the trunk to the line, a signal at the second operator's position, and means responsive to the estab-lishment of a connection to the trunk at the first position during the existence of a connection over the automatic switch at the 95 second position for operating the signal, and means at the second position for reestablishing the initial condition of the signal.

17. In a telephone system, first and second operators' positions, an automatic switch, a line, a trunk connecting the two positions, means including the automatic switch for setting up a connection from the trunk to the line, a signal at the second operator's position, means responsive to the estab-lishment of a connection to the trunk at the first position during the existence of a connection over the automatic switch at the second position for operating the signal, means at the second position for releasing the switch, and means at said second position for reestablishing the initial condition of the signal independent of the release of the switch. 100

18. In a telephone system, two operators' positions, an automatic switch, a line, means including the automatic switch for extending a call to the line, means for releasing said automatic switch, means under the control of one of said operators for operating the releasing means, means under the control of the last mentioned operator for trans-ferring the control of the releasing means to the other operator, and means effective after the call has been answered for rendering the control by said other operator subject to the 120 control by the called party.

19. In a telephone system, two operators' positions, an automatic switch, a line, means including the automatic switch for extending a call to the line, means for releasing said 130

automatic switch, means under the control of one of said operators for operating the releasing means independent of the called party, means under the control of the last 5 mentioned operator for transferring the control of the releasing means to the other operator, and means effective after the call has

been answered for rendering the control by said other operator subject to control by the called party.

In witness whereof, I hereunto subscribe my name this 7th day of November, A. D., 1921.

CLARENCE E. LOMAX.
